CLAIM

The ornamental design for a container for food, as shown and described.

DESCRIPTION

FIG. 1 is a top, side and front perspective view of a container for food showing my new design;

FIG. 2 is a bottom, side and rear perspective view thereof;

FIG. 3 is a top plan view thereof;

FIG. 4 is a bottom plan view thereof;

FIG. 5 is a right side elevation view thereof;

FIG. 6 is a left side elevation view thereof; and,

FIG. 7 is a front elevation view, the rear elevation being a mirror image thereof.
